[57] CLAIM

The ornamental design for a combined utility and recreational trailer, substantially as shown.

DESCRIPTION

FIG. 1 is a side elevation view of a combined utility and recreational trailer showing my new design, the opposite being a mirror image thereof;

FIG. 2 is a top plan view thereof;

FIG. 3 is a front elevational view thereof;

FIG. 4 is a rear elevational view thereof;

FIG. 5 is a side elevational view thereof with the top removed;

FIG. 6 is a top plan view of FIG. 5;

FIG. 7 is a front elevational view of FIG. 5; and

FIG. 8 is a rear elevational view of FIG. 5.
